Figure 8 consists of a large L-shaped polygon labeled 45 at the top. Below it is a smaller L-shaped polygon labeled 44. To the left of the large L-shape is a horizontal bar divided into two segments: the top segment is labeled 41 and the bottom segment is labeled 42. The entire diagram is labeled "Fig. 8" in cursive script.

UNITED STATES PATENT OFFICE.

EDOM WILLIAMS, OF LOUISVILLE, KENTUCKY.

POULTRY FEEDER.

Application filed November 27, 1925. Serial No. 71,572.

The invention relates to feeding devices operated by the fowls, for dispensing the feed in limited quantities as required, and the object of the invention is to provide a simple inexpensive device of this character, automatically operated by the fowls, and in which the feed is efficiently protected and delivered in the desired small quantities necessary to provide the required ration without waste.

Another important object is to provide means for varying or regulating the quantity delivered at each operation in accordance with the requirements of the flock, and for scattering the feed as it is delivered.

The invention consists in certain novel features and details of construction and arrangement by which the above and other objects are attained, to be hereinafter described and claimed.

The accompanying drawings form a part of this specification and show an approved form of the invention.

Figure 1 is a side elevation of the feeder.

Figure 2 is a front elevation.

Figure 3 is a plan view of the same.

The remaining figures are on a larger scale and show the reservoir or hopper in detail.

Figure 4 is a rear elevation of the reservoir.

Figure 5 is a plan view with the cover removed.

Figure 6 is a transverse vertical section taken on the line 6—6 in Figure 4 and partly in elevation.

Figure 7 is a longitudinal vertical section taken on the line 7—7 in Figure 6 and partly in elevation.

Figure 8 is a face view of a plate used in varying the delivery from the reservoir.

Similar reference numerals indicate the same parts in all the figures.

The base of the device comprises a tubular nipple 10 on the lower end of which is screwed a T 11 having in each lateral branch a bent leg 12, and on the upper end of the nipple a cross connection 13 having in each lateral branch a similar but slightly longer bent leg 14, the arrangement being such that by turning the T 11 relatively to the cross connection 13, the legs 12 may be turned beneath and in the same vertical plane with the legs 14 for convenience in packing.

A second nipple 15 is screwed into the upper vertical branch of the cross connection

13, and screwed thereon is a T 16 with its branch presented laterally and receiving a stud 17 serving as a pivot for a lever 18 mounted to tilt thereon with its arms extended in opposite directions therefrom.

A standard 19 is screwed into the upper branch of the T 16 and extends vertically to a T 20 in the lateral branch of which is screwed an arm 21 terminating in a fork 22 having a pin 23 in the branches thereof. A short portion 24 of the standard is screwed into the T 20 and terminates in a reducing elbow 25 from which extends a horizontally disposed fixed shaft or arm 26 above and parallel with the arm 21 and carrying the feed reservoir 27 mounted to oscillate thereon.

The reservoir 27 is preferably in the form of a rectangular box, and on the side face 75 adjacent the elbow 25 and near each end of such face, is a stud 28 and 29 adapted to receive each end of depending flexible connections, shown as light chains 30 and 31, the lower ends of which are attached each to one of the arms of the tilting lever 18, the arrangement being such that a tilting movement of the lever causes a corresponding oscillation of the reservoir thus elevating the ends of the latter alternately. Short chains 80 35 extending from a central stud 36 to points on the chains 30 and 31 limit the oscillating movements, and the points of attachment of the chains 30 and 31 to the arms of the lever 18 are adjustable thus limiting the movements of the lever.

The shaft 26 extends completely through the reservoir from side to side and the latter is held thereon by nuts 32, the walls being held in spaced relation by a sleeve 33 95 within the reservoir inclosing the shaft. A close fitting removable lid or cover 34 closes the open upper face of the reservoir.

In each end of the reservoir at the junction with the bottom is a long narrow opening or slot 37 communicating with the interior of a rectangular pocket 38 which extends part way up the exterior of the end and has a horizontal duct or channel 39 which extends part way along the bottom of the reservoir, the open ends of such channels facing each other. A narrow ledge 40 on the interior of the reservoir immediately above each slot 37 serves in directing the feed to the slot as the reservoir is inclined at each 105 110 oscillation.

In order to govern the amount of feed

delivered to the channels through the slots 37, a regulator 41 is inserted in each of the vertical pockets 38; the regulator shown consists of a rectangular plate having a rectangular notch 42, 43, 44 and 45, in each side. The notches vary in size and the one presented lowermost registers with the slot 37 so that the effective opening in the latter may be varied by inserting the regulator in the pocket with the desired notch down. The regulators are held lightly in position by the frictional engagement of the bosses formed by depressing the exterior faces of the pockets as at 46, see Figures 2, 5 and 7, so that the regulators may be readily removed and reinserted to vary the delivery.

The operation is as follows:—The device is set up in the poultry yard as in Figures 1, 2 and 3, the regulators 41 inserted with the selected notch presented at the slot 37, and the reservoir 27 partly filled with the grain to be delivered. At each oscillation of the lever 18, due to the weight of a fowl on the elevated arm thereof, the reservoir 27 is correspondingly tilted through the pull on one of the chains 30 and 31 and the grain in the correspondingly elevated channel 39 escapes and descends upon the deflector 47, shown as a cone suspended from the pin 23 in the fork 22 of the arm 21, and is scattered thereby in all directions upon the ground or litter of the poultry yard. The next descent of the high end of the lever delivers a charge of grain from the opposite channel 39, and so on until the supply in the reservoir is exhausted.

By governing such supply and its delivery through the channels 39 the quantity may be readily determined for the needs of a given number of fowls for a full day's ration. The grain is protected against damage or waste and the fowls soon learn to operate the device so that feeding is automatically performed and the grain judiciously distributed throughout the day or other period.

When the device is first installed it is necessary to attach pieces of meat or other bait, not shown, at high points on the chains 30 and 31 to induce the fowls to hop upon the lever 18, but when the fowls learn that each such action on the high arm of the lever produces a shower of grain, the baiting may be discontinued.

The apparatus is simple in construction and operation; it keeps the feed clean and avoids waste while fully supplying the needs of the flock by successive deliveries of the feed in small quantities.

The downward movements of the arms of the tilting lever 18 are in practice limited by striking upon the litter usually spread upon the floor of the poultry yard. The chains 35 should be so adjusted relatively to the chains 30 and 31 as to permit such descent

but also to prevent excessive tilting of the reservoir when the chains 30 and 31 are attached to the lever arms at points further from the fulcrum.

The ledges 40 in addition to directing the grain to the slots 37 serve the important function of holding back on the flow when the reservoir is full, and thus prevent the grain from running through and spilling from the high end of the reservoir. 75

I claim:—

1. A rockably-mounted reservoir, adapted to contain feed and deliver a portion thereof at each oscillation, a tilting lever below said reservoir, and connections from said lever to said reservoir whereby the tilting movements of said lever oscillate said reservoir and flexible connections between said connections and a common means on the reservoir for limiting the oscillations of the 85 reservoir.

2. A rockably-mounted reservoir, adapted to contain feed and deliver a portion thereof at each oscillation, a tilting lever below said reservoir, connections from said lever to said reservoir whereby the tilting movements of said lever oscillate said reservoir, flexible connections between said connections and a common means on the reservoir for limiting the oscillatory movements of the 95 reservoir, and a deflector beneath said reservoir arranged to scatter the feed thus delivered.

3. A standard, a reservoir pivotally mounted to oscillate on a shaft thereon and adapted to contain feed and deliver a portion thereof at each oscillation, an arm on said standard, a lever pivotally mounted on the arm of said standard, connections from said lever to said reservoir whereby tilting 105 movements of said lever are transmitted to said reservoir, and a deflector carried by said standard beneath the delivery points of said reservoir.

4. An elevated reservoir mounted to oscillate, adapted to contain feed and deliver a portion thereof at each oscillation, means substantially as described for inducing such oscillations, and means substantially as described for varying the quantity of such 110 portions.

5. A reservoir mounted to oscillate and adapted to contain feed, a pocket on said reservoir in communication with the interior of the latter, a delivery channel leading 120 from said pocket, means in said pocket for governing the amount of feed received in said pocket, and means for oscillating said reservoir.

6. A reservoir mounted to oscillate and 125 adapted to contain feed, a slot in said reservoir, a pocket on the latter in communication with the interior of said reservoir through said slot, a delivery channel leading from said pocket, means in said pocket for va- 130

rying the effective area of said slot, and means for oscillating said reservoir.

7. A reservoir mounted to oscillate and adapted to contain feed, a pocket on each 5 end of said reservoir in communication with the interior of said reservoir through a slot in the latter, a delivery channel for each of said pockets, a plate received in each of said pockets, each of said plates having 10 notches arranged to register with and vary the effective area of the adjacent slot, and means for oscillating said reservoir.

8. A reservoir mounted to oscillate and adapted to contain feed, a pocket on each 15 end of said reservoir in communication with the interior of said reservoir through a slot in the latter, a delivery channel for each of said pockets, a plate received in each of said pockets, each of said plates having 20 notches arranged to register with and vary the effective area of the adjacent slot, means for separably engaging such plate with its pocket, and means for oscillating said reservoir.

9. An elevated reservoir mounted to oscillate and adapted to contain feed and deliver a portion thereof at each oscillation, a tilting lever below said reservoir, connections from said lever to said reservoir whereby the movements of said lever oscillate said reservoir, and means for adjusting the points of attachment of said connections on said lever and thereby governing the extent of its tilting movements. 25

10. An elevated reservoir mounted to oscillate and adapted to contain feed and deliver a portion thereof at each oscillation, a tilting lever below said reservoir, connections from said lever to said reservoir whereby the movements of said lever oscillate said reservoir, means for adjusting the points of attachment of said connections on said lever and thereby governing the extent 30 40 45 of its tilting movements and limiting such movements.

In testimony that I claim the invention above set forth I affix my signature hereto.

EDOM WILLIAMS.
